UNITED STATES PATENT OFFICE.

HARRY VISSERING, OF KENILWORTH, AND GUILFORD S. TURNER, OF BERWYN, ILLINOIS, ASSIGNORS TO HARRY VISSERING AND COMPANY, OF CHICAGO, ILLINOIS, A CORPORATION OF ILLINOIS.

TRACK-SANDING APPARATUS.

Application filed January 15, 1925. Serial No. 2,501.

This invention relates broadly to fluid pressure operated sanders for applying sand to rails to increase the traction of the wheels of railway locomotives and the like.

- 5 In railway locomotive sanders, particularly of the pneumatic type generally in use, difficulty has been experienced in delivering sand to the points on the rails where the best results could be obtained. In the sanders 10 known to us, even though pneumatically operated, a considerable portion of the sand, where a high wind is blowing, fails to reach the rail, because the sand flows principally by gravity through the sand pipe and tends 15 to fall too slowly from the outlet, and is either blown away before it reaches the effective points of utilization or diverted so it falls beside the rail head, rather than upon the traction surface of the rail.
- 20 The primary object of the present invention is to provide an improved apparatus which will effectively deliver the sand at high velocity in close proximity to the points of contact of wheels and rails, and thus overcome 25 ineffective sanding and its resultant waste.

Other objects of the invention are, to provide improved sand ejecting means; improved means for extruding the sand from that in the receiving chamber of the trap, which will not 30 become clogged; and an improved sand trap which is efficient in operation. Other objects of the invention will appear from the detail 35 description.

The invention consists in the several novel 40 features hereinafter set forth and more particularly defined by claims at the conclusion hereof.

In the drawings: Fig. 1 is a diagrammatic 45 elevation of a steam locomotive equipped with the invention; Fig. 2 is a longitudinal, vertical sectional view of a double sand trap embodying the invention. Fig. 2^a is an enlarged section through the nozzles for delivering 50 fluid under pressure into the sand receiving chamber of the trap. Fig. 3 is a horizontal section of the structure shown in Fig. 2. Fig. 4 is a transverse section taken on line 4-4 of Fig. 2. Fig. 5 is a perspective view 55 of a single sand trap embodying the invention. Fig. 6 is an end elevation of the device shown in Fig. 5. Fig. 7 is a sectional view taken on line 7-7 of Fig. 6. Fig. 8 is a horizontal sectional view taken on line 8-8 of Fig.

7. Fig. 9 is a detail plan of a portion of the 55 double sand trap shown in Fig. 2. Fig. 10 is a section on line 10-10 of Fig. 2.

The single sand trap exemplified in Figs. 5 to 8 inclusive usually comprises a cast body B which is provided with transverse holes 5 for bolts to secure the trap in position adjacent the sand dome 8 of the locomotive 9. A chamber 10 formed in body B is connected and adapted to receive sand in any suitable manner from the dome 8 through a port 11. The outer end of chamber 10 is formed by a removable screw-plug 13, so access may be had to said chamber for cleaning or other purposes. Body B of the trap is formed with an enlarged portion b' in which is formed an upwardly inclined passageway or duct 14, through which the sand from chamber 10 is lifted. A cylindrical lining 15 of soft wear-resistant metal, such as lead, is provided around the way 14. The axis of passageway 14 is transverse to the axis of chamber 10 and port 11 and is inclined upwardly therefrom. A chamber 16, formed in body B, is provided to receive, through a downwardly extending conduit 17, sand from passageway 14. A removable screw-cap 18, in an opening 19, forms the upper end of passageway 14 and conduit 17 and provides access thereto. A liner 20 of soft wear-resisting material, such as lead, is positioned and shaped in said cap to deflect 85 the rising sand from passageway 14, downwardly through conduit 17 into chamber 16. The latter has an outlet in its front side into which is threaded an outlet pipe-section 22, which is provided with a cylindrical wear-resisting lining or sleeve 23 of lead or the like. This lining extends from a point adjacent to one end of said section, to a point adjacent the other end thereof, and is confined in an internal enlargement or recess 24. In 90 making this section, the metal to form the liner is poured into the pipe through an inlet 25. A vent 26 is provided to permit the ductile metal to flow into all parts of the recess. The metal in inlet 25 and vent 26 serves to anchor the liner in the pipe section. A suitable core is placed in the pipe section 95 while the liner is being poured into it.

A nozzle 27, substantially coaxial with way 14, is provided to direct a jet of air longitudinally through said way 14 and lift the sand out of the chamber 10 and force it through passageway 14 and conduit 17 into 100

the ejector chamber 16. This nozzle 27 is arranged to initially extrude the sand passing into chamber 10 from the dome and force it through way 14 and conduit 17 into the 5 ejector chamber. In practice, it has been found that when the nozzle 27 is provided with a small jet opening, large particles of sand will settle into such opening and sometimes become lodged therein with sufficient 10 security to clog the jet and thus render the lifting operation inefficient. To overcome this difficulty, a comparatively large opening 27^a (Fig. 7) is formed in the nozzle. A pipe 29 delivers air under pressure into an inlet 15 duct b² formed in one end of body B. A nozzle 27^b in duct b² has an opening sufficiently small to restrict and jet the air into a downwardly extending passageway b³ in body B which has its lower end inclined and in communication with the inlet side of lifting nozzle 27. The axis of the jet opening in nozzle 27^b is longitudinal of the duct b². As a result of employing the nozzle 27^b with a restricted jet-opening in the supply conduit, 20 and a lifting nozzle with a relatively large opening, it becomes practically impossible for the large particles of sand to prevent the delivery of air in the desired volume and velocity through chamber 10 and passageway 25 14, because the sand cannot reach the opening in nozzle 27^b, which is elevated for that purpose. Access may be had to nozzle 27^b for cleaning or replacement through an opening in the top of body B which is normally closed 30 by a screw-plug 27^c. Access may be had to the lower end of conduit b³ and the inner end of nozzle 27 through an opening in the body B, which is normally closed by a plug 27^d.
An ejector nozzle 30 is arranged to discharge a jet of air under pressure axially into and longitudinally of the pipe 22 to project and impel the sand delivered into the 40 ejector-chamber 16 under a high velocity throughout the entire length of the delivery-pipe, so that it will be forcibly projected from the exit of the delivery pipe to the point of contact between the traction-wheel and the rail. In practice, it has been found that the use of a jet 30 in conjunction with 45 a jet for extruding the sand from the trap will attain this desired result. Nozzle 30 is connected to receive air from a conduit 31 in a member D. In practice, it is desirable, in some instances, to apply the present invention to certain existing types of sand domes and, for that purpose, the member D is formed to serve as an adapter between the body or casing B and the dome structure, the 50 holes 5 being extended through the adapter so that the attaching bolts 5^a will conjointly secure said body and adapter in place. A pipe 32 is adapted to deliver air under pressure into duct 31. Pipe 29, for supplying compressed air to the nozzles 27^b and 27, is connected to said casing B. This construc-

tion, with pipes separately supplying air to the sander and lifter and the ejector nozzles, is adapted for use in instances where separate control of the jets is desired.

In Figs. 1 to 4 inclusive, the invention is exemplified in a double trap suitable for use on a single sand dome for sanding the front or to the rear of the driving wheels respectively, as may be desired. The casing B' forms two of the single traps shown in Figs. 5 to 8, which are arranged end-to-end and are integrally formed, but relatively reversed, so that the structure will be compact and may be easily installed. Each trap in this double construction will be provided with nozzles 27^b and 27, a chamber 10, passageway 14, conduit 17 and an ejector nozzle 30, like those described in the single trap construction. In this form of the invention, the adapter D is dispensed with. The outlet pipe-section 22 of one of the traps is connected to deliver the sand from one of the ejector chambers 16 to a delivery pipe 34 for sanding one of the rails in front of one of the drivers 35. The pipe-section 22, which leads from the ejector chamber 16 of the other trap, is connected to a delivery pipe 33, which is adapted to sand the rail in the rear of one of the drivers or traction-wheels 35.

In the form of the invention exemplified in Figs. 1 to 4, the ejector nozzles 30 are supplied with compressed air from ports b²⁰, to which air is delivered through pipes 29 respectively. The ducts 31^a, which deliver air to the ejector nozzles, lead from the ports b²⁰, respectively, so that compressed air will be conjointly supplied to the lifter and ejector nozzles and so that a single controlling device or valve will simultaneously control the operation of all of the nozzles in one trap. In this construction, a clean-out plug 31^b may be provided for each duct 31^a.

In the construction shown in Fig. 1, the pipe 29 is formed as a branch of a pipe 49, which is connected to a suitable controller valve C and which is adapted to supply compressed air to the front sanders at either side of the dome. Pipe 29 of the rear trap in each body B' is a branch of a pipe 50 which is connected to the controller valve C to supply air under pressure for the operation of the rear sander. Pipe 50 is also connected to the corresponding sander at the other side of the dome. A pipe 51 supplies compressed air from a suitable source to the controller valve C, as well understood in the art.

The invention exemplifies an improved sander, in which provision is made for extruding sand from the trap with means for projecting sand in sufficient velocity through the delivery pipes to cause the sand to be reliably delivered in close proximity to the points of contact between the wheels and the rails. The invention also exemplifies an improved pneumatic lifting means for the sand,

in which provision is made to prevent the lifting nozzle from becoming clogged or inoperative. The invention also exemplifies a sander in which provision is made for 5 jointly supplying sand to the ejector and lifting nozzles so that they may be unitarily controlled.

The invention is not to be understood as restricted to the details set forth, since these 10 may be modified within the scope of the appended claims, without departing from the spirit and scope of the invention.

Having thus described the invention, what we claim as new and desire to secure by Letters Patent, is:

1. In sanding apparatus, the combination of a casing having an inlet in one side thereof for delivering sand transversely into the casing, a chamber for receiving the sand, an outlet chamber, and a longitudinally extending trap-conduit between said chambers, an air jet disposed in the receiving chamber to force sand through the conduit into the outlet chamber, an air jet disposed in said outlet 25 chamber to impel sand therefrom, and a connection for delivering air under pressure to said jets.

2. In sanding apparatus, the combination of a casing provided with a sand receiving 30 chamber, an outlet chamber, and a longitudinally extending trap-conduit between said chambers, a delivery pipe connected to one side of the casing and in communication with the outlet chamber, an air jet in said receiving chamber to force sand through said conduit into the outlet chamber, a transversely extending air jet in said outlet chamber to impel sand therefrom into the pipe, and a connection for delivering air under 35 pressure to said jets.

3. In sanding apparatus, the combination of a casing having an inlet in one side thereof for delivering sand transversely into the casing, a transversely extending chamber for receiving the sand, a transversely extending outlet chamber, and a longitudinally extending trap-conduit between said chambers, a delivery pipe connected to the other side of the casing and in communication with said 45 outlet chamber, an air jet in said receiving chamber to force sand through the conduit into the outlet chamber, a transversely extending air jet disposed in said outlet chamber to impel sand therefrom and into the pipe, and a connection for delivering air under 50 pressure to said jets.

4. In sanding apparatus, the combination of a casing having a sand receiving chamber, a transversely extending outlet chamber, and 55 a longitudinally extending trap-conduit inclined upwardly from the receiving chamber and thence downwardly to the outlet chamber, said trap conduit extending at substantially right angles to said outlet chamber, an 60 upwardly inclined air jet in the receiving

chamber to force sand through the conduit into the outlet chamber, a transversely extending air jet for impelling said sand from the outlet chamber, and a connection for delivering air under pressure to said jets. 70

5. In sanding apparatus, the combination of a casing having a sand receiving chamber, an outlet chamber extending substantially parallel to said receiving chamber, and an angular trap-conduit extending between and at substantially right angles to said chambers, an air jet in the receiving chamber to force sand through the conduit into the outlet chamber, an air jet for impelling the sand from the outlet chamber, and a connection for delivering air under pressure to said jets. 75

6. In sanding apparatus, the combination of a casing having an inlet in one side thereof for delivering sand transversely into the casing, a chamber for receiving the sand, an outlet chamber extending substantially parallel to said receiving chamber, and a longitudinally extending trap-conduit between said chambers, a delivery pipe connected to the other side of said casing and in communication with said outlet chamber, an air jet in the receiving chamber to force sand through the conduit into the outlet chamber, a transversely extending air jet for impelling sand from the outlet chamber, and a connection for delivering air under pressure to said jets. 80

7. In sanding apparatus, the combination of a casing provided with a sand receiving chamber and a trap-conduit, an upwardly extending lifter jet in said chamber having a relatively large discharge opening, and a jet having a restricted discharge opening mounted in the casing, and connected to deliver fluid to the lifter jet. 85

8. In sanding apparatus, the combination of a casing provided with a sand receiving chamber and a trap-conduit, an upwardly extending removable lifter nozzle in said chamber having a relatively large jet opening, and a nozzle having a restricted discharge opening mounted in the casing and connected to deliver fluid to the lifter nozzle. 90

9. In sanding apparatus, the combination of a casing provided with a sand receiving chamber and a trap conduit, an upwardly extending lifter jet in said chamber, having a relatively large discharge opening, and a nozzle having a restricted discharge opening mounted in the casing above the lifter jet and connected to deliver fluid to the lifter jet. 100

10. In sanding apparatus, the combination of a casing provided with a sand receiving chamber and a trap-conduit, a removable lifter nozzle in said chamber having a relatively large discharge opening and a removable nozzle having a restricted discharge opening, mounted in the casing and above the lifter nozzle and connected to deliver fluid to the lifter nozzle. 115

11. In sanding apparatus, the combination 120

- of a casing having an outlet chamber extending transversely therethrough, and a trap-conduit for delivering sand to said chamber, a member fitting against one side of the casing and closing one end of said outlet chamber, an air jet connected to said member and adapted to impel sand from said chamber and through the other end thereof, and means for delivering air under pressure to said jet.
- 10 12. In sanding apparatus, the combination of a casing having an outlet chamber extending transversely therethrough, and a trap-conduit for delivering sand to said chamber,

a member fitting against one side of the casing and closing one end of said outlet chamber, a jet connected to said member and projecting into the outlet chamber, said jet being adapted to impel sand from said chamber and through the other end thereof, and means for delivering air under pressure to said jet. 15 20
